UNITED STATES PATENT OFFICE.

STANISLAW RONDA, OF ERIE, PENNSYLVANIA.

CREASING DEVICE FOR TROUSERS.

1,083,032.

Specification of Letters Patent.

Patented Dec. 30, 1913.

Application filed July 31, 1913. Serial No. 782,213.

To all whom it may concern:

Be it known that I, STANISLAW RONDA, a subject of the Czar of Russia, residing at Erie, in the county of Erie and State of Pennsylvania, have invented certain new and useful Improvements in Creasing Devices for Trousers, of which the following is a specification, reference being had therein to the accompanying drawing.

10 This invention relates to a creasing device for trousers, and the primary object of my invention is to provide a simple and durable device that can be easily placed in the leg of a pair of trousers to crease the same.

Another object of this invention is to provide an extensible frame that can be placed in the legs of trousers for creasing the same and permit of the trousers being 20 suspended from a suitable support.

A further object of this invention is to provide a creasing device that is durable, easy to adjust and highly efficient for the purposes for which it is intended.

25 I attain the above and other objects by a mechanical construction that will be hereinafter specifically described and then claimed and reference will now be had to the drawing, wherein:

30 Figure 1 is a front elevation of the creasing device, Figs. 2 to 4 inclusive are enlarged cross sectional views of the device, Fig. 5 is a perspective view of a portion of the device.

35 A creasing device in accordance with this invention comprises two longitudinal frames 1 that are channel-shaped or U-shaped in cross section. Pivotaly mounted in the frames 1, adjacent to the lower ends

40 thereby by transverse pins 2 are spreader bars 3 that have the ends thereof pivotally connected, as at 4 to an adjusting bar 5. The upper end of the adjusting bar has one edge thereof provided with angularly disposed and equally spaced slots 6 and at the upper end of said bar there is a loop or handle 7.

Slidably mounted upon the upper end of

the bar 5 is a locking bar 8 that is slotted, as at 9 and the slotted portion bent outwardly to form a tooth 10 adapted to engage in one of the slots 6 and lock the bar 8 relatively to the bar 5. The upper end of the locking bar 8 has a loop or handle 11 and the lower end thereof has straps 12 that 55 embrace the adjusting bar 5.

Pivotaly connected to the lower end of the locking bar 8, as at 13 are spreader bars 14 and these bars are pivotally mounted in the frames 1, as at 15.

60 The upper ends of the frames are provided with arms 16 and 17, the arm 16 having a strap 18 that embraces the arm 17 and the arm 17 a strap 19 that embraces the arm 16, whereby said arms will connect the 65 upper ends of the frames 1 to permit of said frames being extended or retracted relatively to the bars 5 and 8. The bars 5 and 8 pass between the arms 16 and 17 and the straps thereof, as best shown in Fig. 2. 70

With the frames 1 in a retracted position, as shown by dotted lines in Fig. 1 the device can be easily placed in a trouser leg. By then shifting the bar 8 relatively to the bar 5 the spreader bars 3 and 14 extend the 75 frames 1 whereby said frames will frictionally engage a trouser leg and crease the same. The bar 8 is locked in adjusted position relatively to the bar 5 by the tooth 10 engaging in one of the slots 6. The handles 80 or loops 7 and 11 permit of the device being suspended from a suitable support.

The device in its entirety can be made of light and durable non-corrodible metal and can be constructed upon a smaller scale and 85 used as a sleeve creasing device.

What I claim is:

A trouser creasing device comprising channel frames, sets of spreader bars pivotally connected to said frames, an adjusting bar pivotally connected to one set of spreader bars and having the upper end thereof provided with a plurality of slots, a locking bar slidably mounted upon said adjusting bar and having the lower end 95 thereof pivotally connected to the other set

of spreader bars, a tooth carried by said locking bar and adapted to engage in one of the slots of said adjusting bar, loops carried by the upper ends of said bars, and arms connected to the upper ends of said frames and slidably connected together with said bars passing between said arms.

In testimony whereof I affix my signature in the presence of two witnesses.

STANISLAW RONDA.
